DESIGN FOR A PILE FABRIC

Harold E. Wadeley, Scarsdale, N. Y.

Application February 24, 1941, Serial No. 99,169

Term of patent 3½ years

To all whom it may concern:

Be it known that I, Harold E. Wadeley, a subject of the King of Great Britain and a resident of Scarsdale, in the county of Westchester and State of New York, have invented a new, original, and ornamental Design for a Pile Fabric, of which the following is a specification, reference being had to the accompanying drawing, forming part thereof.

The figure is a plan view of a pile fabric showing my design.

I claim:

The ornamental design for a pile fabric as shown.

HAROLD E. WADELY.
